W. R. DENMAN,
YARN COATING DEVICE,
APPLICATION FILED JULY 27, 1916.

1,206,420.

Patented Nov. 28, 1916.

Inventor:

Walter R. Denman,

Atty's.

UNITED STATES PATENT OFFICE.

WALTER R. DENMAN, OF AKRON, OHIO, ASSIGNOR TO THE MILLER RUBBER COMPANY,
OF AKRON, OHIO, A CORPORATION OF OHIO.

YARN-COATING DEVICE.

1,206,420.

Specification of Letters Patent. Patented Nov. 28, 1916.

Application filed July 27, 1916. Serial No. 111,674.

To all whom it may concern:

Be it known that I, WALTER R. DENMAN, a citizen of the United States, and resident of Akron, Ohio, have invented certain new and useful Improvements in Yarn-Coating Devices, of which the following is a specification.

My present invention relates to improvements in yarn or thread coating apparatus and has among its objects to provide a simple, economical, and efficient form of means by which a maximum number of threads may be immersed for a considerable period while on their way to the twisting apparatus without requiring an excessive quantity of coating or impregnating material.

Another object is to provide an apparatus for the purpose described, which will occupy a minimum amount of space and which can be easily and quickly manipulated.

I have also designed the apparatus with a view to facilitating the passage of any knots in the thread without breakage while at the same time removing any surplus coating medium.

With these and other objects in view the invention includes the novel features of construction and arrangement and combination of parts hereinafter described and particularly defined by the appended claims.

An embodiment of my invention is illustrated in the accompanying drawings, in which—

Figure 1 is a front view of my preferred form of apparatus, and Fig. 2 is an end view, partly broken away.

Referring by reference characters to this drawing, the numeral 1 designates a tank which is of U-shape and is preferably made of sheet metal with parallel inner and outer walls. It is made of a length sufficient to handle a large number of threads and of considerable height as shown, being normally filled to the level, indicated in the drawing. The threads or cords to be coated or impregnated, which are indicated at 2, are led from any suitable source of supply (not shown) to a rounded bearing member, or guide 3, secured to one longitudinal edge of the tank, such bearing member being provided with spacing devices such as pins 4, between which the individual threads pass. From this edge the threads pass

downward through one leg of the tank, around beneath the upper curved wall of its lower part, and thence up through the other leg to its upper edge, where they pass over a rounded bearing surface, such as a horizontal pipe 5, whence they are led to the drying oven or other point of further treatment or use (not shown). By providing a tank of U-shape having the spaced upright chambers of material height communicating at the bottom, I am enabled to subject a very long portion of each thread to the impregnating or coating action, and thus may impart considerable speed to the thread feeding devices. Further I provide a tank which occupies but little floor space and which also does not require an excessive amount of liquid to fill it to the required height.

To enable the advanced ends of the threads to be passed through the tank, a shaft 6 is journaled in suitable bearing plates 7 which are bolted to the upper end edges of the tank so as to be capable of vertical adjustment. Secured at or near opposite ends of this shaft are a pair of sprocket wheels 8, over which pass endless chains 9 which extend down through the vertical legs of the trough and through the bottom portion lying beneath the curved inner wall 1^a. These chains carry a cross bar 10 provided with a plurality of spaced hooks 11 corresponding in number to the number of threads to be treated. When the threads are to be passed through the tank their advanced ends are connected with the hooks 11 and the shaft 6 is then rotated by handle 6^a in the direction of the arrow to cause the chains to carry the bar 10 from the position shown in Fig. 2 down the descending leg, across through the bottom portion and up the ascending side until the hooks appear above the bar or tube 5, when the thread ends can be disconnected and connected to the winding roller or other device (not shown).

In front of the guide roller are arranged a plurality of bearing plates or members 12, one for each thread, each having a thread receiving groove 12^a in its upper face. These are secured to the upper edge of the tank by bolts passing through vertically elongated slots which permit vertical adjustment of the bearing members.

Above each bearing plate or member 12 is

a corresponding presser device 13, preferably in the form of an arm pivoted on a horizontal rod 14 supported by brackets 14^a and adapted to be drawn by spring 18 5 toward the corresponding bearing member 12, the outer end of this arm being provided with a groove in its under face registering with the thread receiving groove 12^a. When the thread is passing through the opening 10 formed by these grooves all excess of coating liquid will be removed and will run down the inclined rear face of the bearing member to the point 12^b in which it terminates and will then drop back into the tank. Any 15 knots passing through the groove in 12 and 13 will act against spring 18 and cause member 13 to raise slightly, thus enlarging the groove opening.

To enable the threads to be readily passed 20 through between members 12 and 13 after they have been disconnected from eyes 11, as above described, I provide each arm 13 with a lug or dog 13^a designed to engage, when the arm is lifted, with a spring pawl 15, 25 whereby said arm will be held elevated. A projection 15^a on the pawl enables it to be lifted to release the arm and allow it to drop into yarn-engaging position.

A convenient manner of mounting the dog 30 is to provide it on its under surface with a pair of projections 15^b engaging corresponding recesses in the supporting bar 16 and yieldingly hold it in place by a bolt 17 connected through spring 18 with an eye 19 35 secured in arm 13, the nut 20 on bolt enabling the tension of the spring to be adjusted. As the dog raises it will simply rock on its rearmost projection as a pivot. It will thus be seen that spring 18 serves two 40 purposes as described.

While I have described my device as in connection with the coating or impregnation of threads or yarns, it will be understood that I do not limit myself to such use.

45 What I claim is:—

1. Apparatus for coating or impregnating threads and the like comprising a substantially U-shaped tank having guides at its outer upper edges, endless carriers arranged 50 to travel through said tank, a bar carried by said carriers, and means for securing the threads to said bar.

2. Apparatus for coating or impregnating threads or the like comprising inner and 55 outer walls of U-shape with space between for coating medium, thread guides at the

outer upper edges of the tank, a shaft journaled over the space between the inner walls, sprocket wheels carried by said shaft, endless sprocket chains passing over said wheels and through said tank, a bar carried by said chains, and means for securing the thread ends to said bar.

3. Apparatus for coating or impregnating threads or the like comprising a substantially U-shaped tank having guides at its upper outer edges, endless carriers arranged to travel through said tank, a bar carried by said carriers, means for temporarily securing the threads to said bar, presser devices 65 arranged to bear on the thread on the delivery side, and means for holding said presser devices out of contact with the thread at will.

4. Apparatus for coating or impregnating threads and the like comprising an impregnation tank, means for passing thread there-through, guide means on the delivery side over which the thread passes, a plurality of yielding presser devices for pressing on the 70 threads, and pawls for holding said devices away from the threads.

5. Apparatus for coating or impregnating threads and the like comprising an impregnation tank, means for passing thread there-through, a plurality of thread guides on the delivery side of said tank, pivoted arms carrying presser portions coöperating with said guides, and means for holding said pivoted arms elevated at will.

6. Apparatus for coating or impregnating threads and the like comprising an impregnation tank, a plurality of individually vertically adjustable members on the delivery side thereof, having thread guiding 95 grooves, a plurality of pivoted arms having portions adapted to coöperate with said members, and means for holding said arms elevated.

7. Apparatus for coating or impregnating threads and the like comprising an impregnation tank, a plurality of individually vertically adjustable members on the delivery side thereof having thread guiding grooves, and having inclined pointed portions for returning surplus solution to the 105 tank.

In testimony whereof, I affix my signature.
WALTER R. DENMAN.
